FOLDING COT OR BED WITH CENTRAL LEG

Edward Gottlieb, Brooklyn, N.Y.

Application August 19, 1949, Serial No. 111,227

11 Claims. (Cl. 5—111)

1

This invention relates to new and useful improvements in folding cots or beds.

There is now on the market a certain type of folding cot or bed which has a horizontal mattress support frame composed of at least two sections, namely, a base section and a head section. This type of folding cot or bed is characterized by a pair of cross legs supporting the base section and a single leg supporting the head section, as may be fully understood by inspecting patent of G. J. Fischer, No. 2,231,993. This type of folding cot or bed has tie rods connected to operate the cross legs automatically, when the cot or bed is opened and closed. The major defect of this type of folding cot or bed resides in the mechanical advantage between the substantially horizontal motion of the tie rods which operate the cross legs, and the height of opening and closing of the cross legs. For example, the tie rods move from four to six inches in the horizontal slots, at which point they connect with the cross legs, while the cross legs open and close vertically approximately sixteen inches. This is a ratio of about 1 to 4, or 1 to 3. It is impossible to make the rivets tight which hold the various parts together, as otherwise they would not have the necessary movements, and it is impossible to prevent parts from bending, such as the frame sections, the tie rods, and the cross legs themselves. This play and flexing accumulates sufficient play or motion at the points where the tie rods connect with the cross legs, namely, at the slots, amounting sometimes to as much as one-quarter inch with resultant sag of the cross legs and the central portion of the mattress support frame as much as one inch. Sagging at the center of the cot is highly objectionable when persons lie down and arise from the cot. It is customary to partially correct these defects by making the parts and the rivets of heavier stock. For example, the angle irons used to construct the mattress support frame are usually $1\frac{1}{4}$ inch angles. The cross legs and the tie rods are either of $1\frac{1}{4}$ inch, or $1\frac{1}{2}$ inch angles, or of flat stock of $1\frac{1}{4}$ inches by at least $\frac{3}{8}$ inch.

The dominating object of this invention resides in constructing a superior cot which has no tendency to sag at the middle and which therefore is capable of being constructed of lighter materials and rivets. More specifically, it is proposed to support the mattress support frame with vertical end legs, and with a vertical central leg. Since these legs are in vertical compression when the cot or bed is open, they are in their strongest load carrying positions and therefore may be

2

made of relatively lighter materials. With the new construction taught herein the folding cot or bed may be constructed of one inch angle materials, and one inch by one-quarter inch bars, and be entirely satisfactory. Not only will the new cot or bed be cheaper to manufacture because it utilizes less material, but it will be lighter which is a great advantage, as in the home they are often opened and closed by women.

10 Another important object of this invention resides in so constructing the new folding cot or bed that it may be easily opened and closed, particularly by merely moving the head section from a position over the base section in opening the cot, and moving it back over the base section in closing the cot. In order to obtain this simple operation the central leg has so been positioned in relation to the parts of the cot and arranged to function in a certain way so as to assist the 15 base section in standing up when the cot is opened, and in laying down when the cot is closed.

A further object of this invention resides in the teaching of at least two constructions embodying the features of this invention, one in 20 which the central leg operates automatically, and the other in which the central leg must be manually moved. However, in each of these cases the central leg functions to lower and lift the base section when the folding cot or bed is closed or opened.

25 Another object of the invention is the construction of a folding cot or bed as described, which is simple and durable and which may be manufactured and sold at a reasonable cost.

30 For further comprehension of the invention, and of the objects and advantages thereof, reference will be had to the following description and accompanying drawings and to the appended claims in which the various novel features of the 35 invention are more particularly set forth.

35 In the accompanying drawings forming a material part of this disclosure:

Fig. 1 is a plan view of a folding cot or bed constructed in accordance with this invention and illustrated in a fully opened position.

40 Fig. 2 is a front elevational view of the cot or bed shown in Fig. 1.

Fig. 3 is a fragmentary enlarged vertical sectional view taken on the line 3—3 of Fig. 2.

45 Fig. 4 is a fragmentary enlarged vertical sectional view taken on the line 4—4 of Fig. 2.

50 Fig. 5 is an elevational view similar to Fig. 2 but illustrating the cot as it appears when the head section is moved upwards 90° during the 55 operation of closing or opening the cot or bed.

Fig. 6 is an elevational view similar to Fig. 5 but illustrating the folding cot or bed fully closed, with the head section moved 90° clockwise from the position shown in Fig. 5, to the fully closed position.

Fig. 7 is an elevational view similar to Fig. 5 but disclosing a modified form of my folding cot or bed.

Fig. 8 is a fragmentary enlarged vertical sectional view taken on the line 8-8 of Fig. 7.

The new folding cot or bed, in accordance with this invention, includes a mattress support frame 10 disposed horizontally when the cot or bed is fully open, and having three adjacent horizontal sections 11, 12 and 13 in single file and in end alignment with each other when the cot or bed is in an open position. These three sections are hereinafter designated as a head section, a central section, and a base section, respectively, from one end of the single file to the other. The central section 12 includes a pair of spaced angle irons 14 and 15 arranged with their top flanges horizontal and their side flanges disposed outwards of each other. These angles 14 and 15 are rigidly connected by a cross brace 16 of angle material. This cross brace 16 is of U-shape. It has vertical sides 17 connected by a horizontal section 18. The top ends of the vertical sides 17 are welded to the angles 14 and 15. The base section 13 and the head section 11 are constructed of angle material bent into U-shape in plan view, with the ends of their arms disposed adjacent and inside of the ends of the angles 14 and 15 of the central section 12.

Rivets 20 pivotally connect together the adjacent ends of said adjacent sections 11, 12 and 13. Said adjacent sections 11, 12 and 13 are associated with means for limiting pivoting thereof downwards from said horizontal position, as illustrated in Figs. 1 and 2. This pivot limiting means consists merely in the way the sections 11, 12 and 13 are associated with each other. Namely, the ends of the head section 11 and the base section 13 are set under and inside of the ends of the angles 14 and 15 of the central section 12, and the rivets 20 are positioned outwards of the ends of the head section 11 and base section 13 and inwards of the ends of the angles 14 and 15 of the central section 12. The ends of the angles 14 and 15 of the central section 12 are formed with notched out portions 22 upon the top arms thereof arranged so that head section 11 and base section 13 may pivot upwards from their horizontal positions to positions at right angles to the central section 12.

The central section 12 has an extension extending downwards of the rivets 20 thereof. This extension includes the brace 16 and small horizontal strips 23 mounted upon the bottom portions of the side arms 17 of the brace 16. These strips 23 preferably are just as long as the lengths of the angles 14 and 15. An end leg 25 is pivotally connected with an end portion of the base section 13. An end leg 26 is pivotally connected with the end portion of the head section 11. These end legs 25 and 26 extend downwards for supporting the ends of said horizontal mattress support frame 10. These end legs 25 and 26 are of U-shape. Their horizontal bottom portions rest on the floor, while their vertical arms extend upwards and are pivotally connected with the frame 10 by rivets 27. Central leg 28 is pivotally connected with said central section 12 and extends downwards for supporting the central area of said hori-

zontal support frame 10. Note that the central leg 28 is closer to the pivot rivets 20 of the head section 11 with the central section 12 than to the pivot rivets 20 of the base section 13 with the central section 12. The reason for so locating the central leg 28 is to provide means for resisting bending at the rivets 20 between the head section 11 and the central section 12 to a greater degree than at the rivets 20 between the central section 12 and the base section 13. This resisting to bending action is necessary in the proper closing of the cot as will be explained in the operation later on in this specification. This central leg 28 is shown constructed of channel material. It is also of U-shape arranged with its horizontal bottom resting on the floor and its vertical side arms extending upwards outside of the strips 23. Pintle rivets 29 spaced downwards from the top ends of the leg 28 pivotally connect the leg 28 upon the strips 23.

Tie rods 30 are pivotally connected with the end leg 25 of the base section 13 and with said extension of the central section 12, namely, with the ends of the strips 23 for folding the end leg 25 of said base section 13 to a position under said base section 13 when said central section 12 and said head section 11 are pivoted upwards as a unit to a position at right angles to the base section 13 as illustrated in Fig. 5. It should be recognized that as the head section 11 and central section 12 are pivoted up, the central leg 28 will turn clockwise on the pintle rivets 20 which connect the base section 13 with the central section 12 simultaneous with clockwise turning of the end leg 25 on the pintle rivets 27 so that the base section 13 is lowered substantially in a horizontal position until it is in a fully down position, as illustrated in Fig. 5. Thus the central leg 28 plays an important part in gradually lowering the base section 13 during the folding of the cot or bed.

Tie rods 32 are pivotally connected with the end leg 26 of said head section 11 and with said extension of said central section 12, namely, the ends of the strips 23 for folding the end leg 26 of the head section 11 to a position substantially flat against the top of the head section 11 when said head section is pivoting downwards from the right angle position as illustrated in Fig. 5, to a position parallel to the base section 13 and at right angles to the central section 12, as illustrated in Fig. 6. The central leg 28 is associated with holding means for rigidly holding said central leg 28 in a downward position when said horizontal mattress support frame 10 is in its horizontal position in order to support the center of said support frame 10 when the folding cot or bed is open. This means for rigidly holding the central leg 28 in this form of the invention, comprises tie rods 33 pivotally connected with the top ends of the central leg 28 and with the end leg 26. More particularly, the end leg 26 has lugs 34 (see particularly Fig. 1) extending leftwards therefrom and the left hand ends of the tie rods 33 are pivotally connected with said lugs 34. It is pointed out that when the folding cot or bed is in its open position, the tie rods 33 act as said holding means. However, these tie rods 33 are movable when the folding cot or bed is folded closed and are moved by the motion of the end leg 26 in order that said central leg 28 may be pivoted and folded substantially flat against the top of the head section 11 when said folding cot or bed is folded closed, as shown in Fig. 6.

Casters 35 and 36 are mounted respectively upon the end leg 25 and the tie rods 30 in order to engage the floor and support the cot or bed when in a folded position. Springs 37 are connected with the end leg 26 and extend upwards at an angle and connect with links 38 which are pivotally connected with the head section 11. These springs 37 urge the end leg 26 of said head section 11 into an open position when said cot or bed is opened from a closed position in order to remove said base section 13 as a counter-resistance or weight to the opening of said central leg 28 and said end leg 26 of said head section 11, so that the base section 13 does not move upwards and interfere with the opening of the cot or bed. The links 38 serve to loosely mount the springs 37 so that they exert no tension until the head section 11 is past its vertical position, illustrated in Fig. 5, when the cot or bed is being closed, in order to reduce the tendency of the cot or bed moving away horizontally while it is being closed.

A latch bar 40 is pivotally mounted on the head section 11 and is cooperative with a keeper element 41 mounted upon the base section 13 for latching the folding cot or bed in its closed position, as illustrated in Fig. 6. The mattress support frame 40 is provided with a suitable mattress support element 42 supported in the usual way by small springs 43 connected with the mattress support frame 10.

The operation of the new folding cot or bed may be understood from the following:

Figs. 1 and 2 illustrate the folding cot or bed in its fully opened position. It may be closed by manually gripping the left hand end of the head section 11 and pivoting the head section 11 upwards. It will be found that the central section 12 remains rigidly aligned with the head section 11 so that bending occurs at the rivets 20 between the central section 12 and the base section 13. The reason for this may readily be seen by realizing that gravity holds the base section 13 down, while the head section 11 is being lifted. The resistance to bending is much smaller at the rivets 20 between the central section 12 and base section 13 than at the rivets 20 between the head section 11 and the central section 12, because bending at the rivets 20 between the head section 11 and central section 12 is resisted by the requirement of moving the central leg 28 and by the action of the central leg 28 in being located closer to the pivot of the head section with the central section than to the pivot of the base section with the central section.

When the head section 11 is being pivoted upwards the central leg 28 is moved clockwise, and simultaneously the tie rods 30 pivot the end leg 25 clockwise which results in the base section 13 being lowered until it reaches a position in which it rests upon the casters 35 and 36 as illustrated in Fig. 5. The head section 11 is now vertical and is moved further to the right to continue closing of the cot or bed. However, pivoting now starts about the rivets 20 between the central section 12 and the head section 11, since the notches 22 of the central section 12 prevent further pivoting of the central section 12 relative to the base section 13 past the vertical position. After the head section 11 has been pivoted a short distance past the vertical position, for example 20° or so, the springs 37 become taut. It is pointed out that when the head section 11 is pivoted through the said 20°

the end leg 26 starts closing because of the tie rods 32, and when the end leg 26 starts closing the tie rods 33 start pivoting the central leg 28 clockwise on the pintle rivets 29. The purpose of delaying stretching of the springs 37 is to make certain that the person closing the folding cot or bed has downward pressure on the head section 11 at this time.

With the downward pressure at this time, as just mentioned, the cot or bed will have no tendency to ride towards the right on the casters 35 and 36. It would then not be necessary for the person attempting to close the cot or bed to place a foot against the right hand end of the base section 13 to prevent rolling of the cot or bed. Once the head section 11 has been pivoted past the vertical position, there is a sufficient downward component of pressure to eliminate the necessity of holding the cot or bed from rolling on the casters 35 and 36 while an attempt is being made to close it. It is merely necessary to continue pushing the head section 11 downwards until it reaches the horizontal position illustrated in Fig. 6. During this latter motion, the end leg 26 will close completely and the central leg 28 will pivot around to engage against the top of the head section 11 as illustrated in Fig. 6. The cot or bed is now fully closed.

The cot or bed may be opened merely by gripping the right hand end of the head section 11, reference is being had to Fig. 6, and pivoting the head section 11 upwards. The importance of the springs 37 may now be understood. Without the springs 37, which are now in stretched positions, the resistance of pivoting of the head section 11 about the rivets 20 between the head section 11 and the central section 12 will be relatively large because effort is required during this period to pivot open the central leg 28 and the end leg 26. The only resistance to this pivoting will be the weight of the base section 13. However, in actual practice it was found that the weight of the base section 13 was insufficient to overcome the resistance. It therefore was necessary to step upon the base section 13 to keep it down. This would be highly objectionable because a mattress and sheet are stored on the base section 13 when the cot is in its folded position. It was found that as much as 25 pounds of weight would be necessary on the base section 13 to keep it from pivoting upwards upon the casters 36 as pivots. However, adding this weight to the base section was ridiculous. For this reason the springs 37 were added. These springs 37 immediately tend to pivot open the end leg 26 and the central leg 28. The action of the springs 37 therefore removes the resistance which caused the base section 13 to stand up. Consequently, the base section 13 will remain down upon the floor. The cot or bed may therefore be opened without the necessity of stepping on and holding the base section 13 downwards.

The head section 11 is pivoted upwards during opening of the cot or bed until it reaches the vertical position as illustrated in Fig. 5. Then pivoting is continued until the central leg 28 strikes the floor. The central leg 28 then assists the end leg 25 in camming up the base section 13 and soon the cot or bed assumes the fully opened position illustrated in Fig. 2.

It should be fully recognized that the cot or bed is fully closed and fully opened merely by gripping the head section 11 by its extremity and

pivoting it around over the base section 13 and off of the base section 13. There is no need for touching any parts of the cot or bed or doing any manipulation during opening and closing of the cot or bed.

In Figs. 7 and 8 a modified form of the invention has been disclosed, which distinguishes from the prior form merely in the means for rigidly holding the central leg 28 in its downward position when the horizontal mattress support frame 10 is in its horizontal position in order to support the center of said frame 10 when the folding cot or bed is opened. This holding means comprises a stop member 50 mounted on each arm 17 of the cross brace 16. Each stop member has an end 51 which engages and strikes small narrow strips 52 attached upon the back face of the upper ends of the arms of the central leg 28. Leaf springs 53 are mounted upon the arms 17 and normally engage the other ends of the strips 52. Since the ends of the leg 28 are now firmly held the leg 28 is rigid. This holding means has a movable part or parts, namely, the leaf springs 53 which may be manually pressed inwards so as to free the upper ends of the arms of the central leg 28. Now the central leg 28 may be manually moved upon its pintle rivets 29 to its closed position.

In this form of the invention the tension springs 37 and the strips 38 are not necessary because the central leg 28 is not connected with tie rods to the end leg 26 and therefore there will not be any resistance to opening of the cot or bed which cannot be overcome by the weight of the base section 13.

In other respects this form of the invention is identical to the previous form and like parts are identified by like reference numerals.

The operation of this form of the invention may be understood from the following:

In Fig. 7 the folding cot or bed is shown partially opened. It may be fully closed by pivoting the head section 11 clockwise until the horizontal position is reached. This automatically closes the end leg 26. The central leg 28 is now manually closed by depressing the springs 53 to free the central leg 28 which is pivotally moved around to a position to rest upon the top of the head section 11 similar to the position in which it is shown in Fig. 6.

The cot is opened merely by pivoting the head section 11 counter-clockwise. The central leg 28 will be correspondingly pivoted and will fall by gravity around to the horizontal position shown in Fig. 7, since the ends of the central leg 28 will cam the leaf springs 53 inwards until the strips 52 on the ends of the central leg 28 strike the ends 51 of the stops 50. Now the central leg 28 is latched rigidly in its open position and the cot or bed may be fully opened by pivoting the head section 11 completely counter-clockwise identically in the same fashion described relative to opening the cot or bed from the position shown in Fig. 5. After the cot is fully opened it may be closed by pivoting upwards the outer end of the head section 11. The central section 12 will rigidly pivot along with the head section 11 because the pivoting action takes place about the rivets 20 which pivotally join the central section 12 with the base section 13. The reason for this point of pivoting is that the central leg 28 is closer to the rivets 20 which pivotally connect the head section 11 with the central section 12 than to the rivets 20 which pivotally connect the central section 12 with the

base section 13, and therefore there is a different degree of resistance to bending at the two pivot points, and the one with the lesser resistance will be the point at which pivoting takes place.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

15. In a folding cot or bed, a horizontal mattress support frame having three adjacent horizontal sections in single file and in end alignment with each other when the cot or bed is in an open position, said three sections being designated base, central and head, respectively, from one end of said single file to the other end, means for pivotally connecting together the adjacent ends of said adjacent sections, means for limiting pivoting of said adjacent sections downwards from said horizontal position, said central section having an extension extending downwards of the pivots of said sections, and end leg pivotally connected on each of said head and base sections and extending downwards for supporting the ends of said horizontal mattress support frame, a central leg pivotally connected with said central section and extending downwards for supporting the central area of said horizontal mattress support frame, tie rods pivotally connected with the end leg of said base section and with said extension of said central section for folding the end leg of said base section to a position under said base section when said central section and said head section are pivoted upwards as a unit to a position at right angles to said base section, said central leg and said end leg of said base section acting to lower said base section gradually while said central section and said head section are pivoted upwards to said right angle position, tie rods pivotally connected with the end leg of said head section and with said extension of said central section for folding the end leg of said head section to a position substantially flat against the top of said head section when said head section is pivoted downwards from said right angle position to a position parallel to said base section and at right angles to said central section, holding means for rigidly holding said central leg in a downward position when said horizontal mattress support frame is in its horizontal position in order to support the center of said support frame when the folding cot or bed is open, and said holding means having movable parts movable in order that said central leg may be folded substantially flat against the top of said head section when said folding cot or bed is folded closed.
20. A folding cot or bed as defined in claim 1, in which casters have been mounted upon the leg and upon the tie rods of said base section in order to engage the floor and support the cot or bed when in a folded condition.
25. A folding cot or bed as defined in claim 1, in which said central leg is pivotally connected with said central section at a point downwards of its top end when the cot or bed is in an open position, and in which said holding means includes a movable tie rod pivotally connected with the top end of said central leg and with said end leg of said head section in order that said
30. 35. 40. 45. 50. 55. 60. 65. 70. 75.

holding means is automatically movable to pivot said central leg into its closed position.

4. A folding cot or bed as defined in claim 1, in which said central leg is pivotally connected with said central section at a point downwards of its top end when the cot or bed is in an open position, and in which said holding means includes a movable tie rod pivotally connected with the top end of said central leg and with said end leg of said head section in order that said holding means is automatically adjustable to pivot said central leg into its closed position, and in which a spring urges said end leg of said head section into an open position when said cot or bed is opened from a closed position in order to remove said base section as a counter resistance to the opening of said central leg and said end leg of said head section so that said base section does not pivot upwards and interfere with the opening of said cot or bed.

5. A folding cot or bed as defined in claim 1, in which said central leg is pivotally connected with said central section at a point downwards of its top end when the cot or bed is in an open position, and in which said holding means includes a movable tie rod pivotally connected with the top end of said central leg and with said end leg of said head section in order that said holding means is automatically adjustable to pivot said central leg into its closed position, and in which a spring urges said end leg of said head section into an open position when said cot or bed is opened from a closed position in order to remove said base section as a counter resistance to the opening of said central leg and said end leg of said head section so that said base section does not pivot upwards and interfere with the opening of said cot or bed, and in which said spring is mounted loosely in position in order that it does not stretch until said head section is past its vertical position when the cot or bed is being closed in order to reduce the tendency of the bed or cot moving away while it is being closed.

6. In a folding cot or bed, a horizontal mattress support frame having three adjacent horizontal sections in single file and in end alignment with each other when the cot or bed is in an open position, said three sections being designated, base, central and head, respectively, from one end of said single file to the other end, means for pivotally connecting the adjacent ends of said adjacent sections, means for limiting pivoting of said adjacent sections downwards from said horizontal position, said central section having an extension extending downwards of the pivots of said sections, an end leg pivotally connected on each of said head and base sections and extending downwards for supporting the ends of said horizontal mattress support frame, a central leg rigidly connected with said central section and extending downwards for supporting the central area of said horizontal mattress support frame, tie rods pivotally connected with the end leg of said base section and with said extension of said central section for folding the end leg of said base section to a position under said base section when said central section and said head section are pivoted upwards as a unit to a position at right angles to said base section, said central leg and said end leg of said base section acting to lower said base section gradually while said central section and said head section are pivoted upwards to said right angle position, and tie rods pivotally connected with

the end leg of said head section and with said extension of said central section for folding the end leg of said head section to a position substantially flat against the top of said head section when said head section is pivoted downwards from said right angle position to a position parallel to said base section and at right angles to said central section.

7. In a folding cot or bed, a horizontal mattress support frame having three adjacent horizontal sections in single file and in end alignment with each other when the cot or bed is in an open position, said three sections being designated base, central and head, respectively, from one end of said single file to the other end, means for pivotally connecting together the adjacent ends of said adjacent sections, means for limiting pivoting of said adjacent sections downwards from said horizontal position, said central section having an extension extending downwards of the pivots of said sections, an end leg pivotally connected on each of said head and base sections and extending downwards for supporting the ends of said horizontal mattress support frame, a central leg pivotally connected with said horizontal mattress support frame and extending downwards for supporting the central area of said horizontal mattress support frame, tie rods pivotally connected with the end leg of said base section and with said extension of said central section for folding the end leg of said base section to a position under said base section when said central section and said head section are pivoted upwards as a unit to a position at right angles to said base section, said central leg and said end leg of said base section acting to lower said base section gradually while said central section and said head section are pivoted upwards to said right angle position, tie rods pivotally connected with the end leg of said head section and with said extension of said central section for folding the end leg of said head section to a position substantially flat against the top of said head section when said head section is pivoted downwards from said right angle position to a position parallel to said base section and at right angles to said central section, holding means for rigidly holding said central leg in a downward position when said horizontal mattress support frame is in its horizontal position in order to support the center of said support frame when the folding cot or bed is open, and said holding means having movable parts movable in order that said central leg may be folded substantially flat against the top of said head section when said folding cot or bed is folded closed.

8. In a folding cot or bed, a horizontal mattress support frame having three adjacent horizontal sections in single file and in end alignment with each other when the cot or bed is in an open position, said three sections being designated base, central and head, respectively, from one end of said single file to the other end, means for pivotally connecting the adjacent ends of said adjacent sections, means for limiting pivoting of said adjacent sections downwards from said horizontal position, a foldable end leg connected on each of said head and base sections and extending downwards for supporting the ends of said horizontal mattress support frame, a central leg rigidly connected with said central section and extending downwards for supporting the central area of said horizontal mattress support frame, means for folding closed said end leg of said base section when said central section and

11

said head section are pivoted upwards as a unit to a position at right angles to said base section, and means for resisting bending between said head section and central section when said cot is in its open position and the outer end of said head section is pivoted upwards in order that said head section and central section pivot upwards as a unit in order that said central leg and said end leg of said base section act to lower said base section gradually while said central section and said head section are pivoted upwards to said right angle position.

9. A folding cot as defined in claim 8 in which said means for resisting bending between said head and central sections resides in locating said central leg closer to the pivot between said head

5

10

15

12

and central sections than to the pivot between said central and base sections.

10. A folding cot as defined in claim 8, in which means is provided for folding closed said end leg of said head section when said head section is pivoted downwards from said right angle position to a position parallel to said base section.

11. A folding cot as defined in claim 8, in which means is provided for releasing said rigidly connected central leg, and a pivot for supporting said central leg in order that it may be pivoted to a closed position.

EDWARD GOTTLIEB.
